UNITED STATES PATENT OFFICE.

ANTOINE PADOUE FILIPPI, OF PARIS, FRANCE.

SHIP.

1,299,161.

Specification of Letters Patent.

Patented Apr. 1, 1919.

Application filed August 6, 1917. Serial No. 184,778.

To all whom it may concern:

Be it known that I, ANTOINE PADOUE FILIPPI, a citizen of the French Republic, residing at 132 Avenue du Maine, Paris, France, have invented certain new and useful Improvements in Ships, of which the following is a specification.

The present invention relates to ships including boats, submarine vessels or the like and has for its object to provide means for reducing the resistance presented by water to the progress of the vessel and in certain cases to utilize such means for purposes of propulsion by disturbing the equilibrium of the various pressures to which the vessel is subjected.

The invention comprises a revolving body with double walls which is placed in the fore part of the hull and partly covers the front end of this hull which is made in corresponding form. The revolving body placed in the fore part of hull is rotated by one of the means described hereinafter. Its outer wall is formed with a number of suitably situated openings. The water which enters between the two walls of the revolving body (whether in consequence of the ship's movement or through pressure by means of a pump) escapes through the openings in the outer wall. This escape is effected at great speed. The effect of this escape of water combined with that of the centrifugal force resulting from the rapid rotation of the revolving body is that the resistance to the progress of the ship at the fore is considerably diminished.

If the invention is applied to an already built ship, a special auxiliary engine for actuating the revolving resistance reducing body may be added, or a portion of the motive power produced by the ship's engines may be diverted for the purpose of actuating the said body. In this case, notwithstanding the reduction of the power devoted to the working of the propellers, a beneficial result is obtained, that is to say an increase in the ship's speed in consequence of the considerable reduction of resistance to the ship's progress.

The invention also relates to an additional arrangement intended to complete the effect of the means mentioned above, by reducing the friction between the hull of the

vessel and the water while the ship is in motion.

It is well known that the adhesion of the water to the ship's hull is one of the chief causes of resistance to a ship's progress. The essential means which is the characteristic feature of the present invention consists in surrounding the hull while the ship is in motion with a considerable number of small air bubbles somewhat in the form of an emulsion in the water, so as to obviate the adhesion of the water to the hull.

This result may be effected in different ways. In the following, two methods of effecting the result are described by way of example.

In the accompanying drawings an example is shown in a purely diagrammatic form of two methods of carrying out the invention. It is obvious that in the carrying out of the invention there may be numerous variations. In these drawings the ship's screw which is arranged in the known manner is not shown.

Figure 1 is a diagrammatic sectional view of the apparatus showing the same applied to a submarine vessel.

Fig. 2 is a similar view showing a modified form of the arrangement.

Figs. 3 and 4 illustrate in a purely diagrammatic form and side elevation, partly in section, two hulls furnished with devices for effecting the emulsion of the air bubbles in the water and the distribution of this emulsion around the hull, while the ship is in motion.

In order to carry out the first part of the invention, whatever may be the method of doing so, the fore part 1 of the ship's hull is made in a form similar to that shown in Figs. 1 and 2, which form must necessarily be that of a solid of revolution around 95 which the movable device 2 to which the invention relates turns.

This movable device has the general form shown in Figs. 1 and 2. It has a double wall.

In the method of construction shown in Fig. 1 the movable device 2 is open in front and presents at this point a sort of gill 3 through which the water enters. The outer wall of the device is drilled with a plurality of suitably situated openings 4. Tubular devices forming ajutages or nozzles may be

fixed in the openings 4, in order if it be necessary that the flow of the water may be better guided while the ship is in motion. The device 2 is carried by a shaft which is 5 driven by a suitable motor 6.

The action of this arrangement is as follows: When the ship moves in the direction of the arrow F, the water enters through the gill 3 in the direction of the arrow f and escapes through the openings 4 in the direction of the arrows f'. At the same time, as has been stated, the device 2 is rotated rapidly around the shaft 5. In consequence of the flowing away of the water in the direction of the arrows f'' and of the effect produced by the centrifugal force on the surface of the rotary device 2, the water in which the ship is immersed is driven forcibly in the direction of the arrows. The result, as has 20 been stated is a considerable diminution of the resistance to progress, in consequence of the thin liquid streams being assisted in flowing away by being pressed from behind and drawn along in front.

25 Fig. 2 shows another method of carrying out the invention. The revolving body 7 in this case, is closed in front. Its inner wall is extended at the back by a cylindrical part 7' which fits into a seating I' of the same 30 form provided in the ship's hull 1. As in the first method of construction, openings 8 are formed in the outer wall of the device 7.

At its back end, the cylindrical part 7' carries the rotor 9 of a hydraulic turbine. 35 The injection device 10 of the turbine is fixed to the seating I', that is to say to the ship's hull. A pump 11 on the shaft 12 of which the auxiliary motor is mounted conveys water under pressure into the hydraulic 40 turbine 9-10 through the pipes 13-14. In this way the tube 7' that is firmly connected with the rotor 9 is rotated and consequently the device 7. On the other hand the water having acted in the turbine flows away 45 through the cylinder 7' into the body 7 and passes out through the openings 8. The total area of these openings is determined so as to offer the minimum of resistance to the passage of the water.

50 In this method of carrying out the invention, the rapid flowing of the water through the openings 8 combined with the effect of the centrifugal force determines the deviation of the thin streams of liquid in the direction of the arrows and, consequently the 55 desired diminution of resistance to progression.

The rotation of the movable device may likewise be effected, without recourse to a 60 motor, by mounting suitably situated vanes or wings on the outer wall of the said device.

In this case the movable device would be mounted to run idly on its shaft and the rotation would be effected by the movement 65 of the ship itself.

The effect of these arrangements may be completed as has been stated, by the means shown by way of example in Figs. 3 and 4 viz: in two methods of carrying out the invention in combination with the system 70 which has just been described.

In the method of carrying out the invention shown in Fig. 3 an air-shaft is arranged in the fore part of the ship and connected through a pipe 15 with a junction placed 75 for example in the axis of the gill 3 of the movable device 2. During the movement of the ship in the direction of the arrow F, the air entering the shaft is carried along into the gill and mixes in the movable device 2 with the water which this device sets in motion as a consequence of its rotation. Thus in some sense an emulsion of air is effected in the liquid mass and when the water issues in the direction of the arrows f' 80 through the openings 4 in the revolving body 2, it carries with it the air bubbles which driven by centrifugal force and carried along by the water pass out through the openings 4 at great speed, bubbling around 90 the ship's hull and thus surrounding this hull over a length which depends on various conditions. The air stratum which is thus interposed between the hull and the surrounding medium causes a considerable diminution of the resistance to progression by 95 obviating or at least reducing the friction between the hull and the water at this point.

In the method of construction shown in Fig. 4 the air-shaft communicates through 100 a pipe 16 with a junction placed in the axis of the pipe 13 which connects the pump 11 with the hydraulic turbine 9-10. In this way a sort of aspirating water jet or ejector action is produced, the stream of water 105 forced by the pump 11 causing a suction of air through the pipe 16. The air thus drawn in mixes with the water in the pipes 13 and 14 and in the turbine 9-10. In this way 110 the air and water emulsion is reliably effected. This emulsion is then expelled in the direction of the arrows f' through the openings 8 in the movable body 7. The result obtained is evidently the same as in the preceding case.

115 Instead of being simply drawn in as in an aspirator as has just been stated, the air might be blown into the pipe by a fan or a compressor.

On the other hand, in the case of a submerged submarine vessel other gases than air could be employed for effecting the emulsion with the water, these gases being produced in the interior of the vessel as required, by means of chemical reaction for 125 example.

130 It is fully understood that the drawings illustrate the arrangements to which the invention relates in a purely diagrammatic manner. The means of fixing air-shafts to

the hull particularly in the case of Fig. 1 have not been shown. These fixing means which may be of any kind do not form part of the invention.

5 What I claim and desire to secure by Letters Patent is:—

1. In a ship or vessel as described means for diminishing the water resistance on the hull comprising a revolute member with 10 double walls including an outer wall with jet apertures and an inner wall spaced therefrom the whole being adapted to fit over the forward end of the hull, a hull shaped to fit in the revolute member, a shaft adapted 15 to carry the revolute member, means for revolving said member and a water inlet in said member.
2. In a ship or vessel as described means for diminishing the water resistance on the 20 hull comprising a revolute member with double walls including an outer wall with jet apertures and an inner wall spaced therefrom the whole being adapted to fit over the forward end of the hull, a hull shaped to fit 25 in the revolute member; a shaft adapted to

carry the revolute member, a hydraulic turbine with rotor adapted to drive said revolute member, and means for pumping water under pressure into the said turbine and through the revolute member substantially as described.

3. In a ship or vessel as described means for diminishing the water resistance on the hull comprising a revolute member with 30 double walls including an outer wall with jet apertures and an inner wall spaced therefrom the whole being adapted to fit over the forward end of the hull, a hull shaped to fit in the revolute member, a shaft adapted to carry the revolute member, means for revolving said member, a water inlet in said member and means for forcing air or gas 35 into the water passing through the revolute member for the purpose described.

In testimony whereof I have affixed my 40 signature in presence of a witness.

ANTOINE PADOUE FILIPPI.

Witness:

CHAS. P. PRESSLY.
